(57) **CLAIM**

The ornamental design for a walking treadmill, as shown and described.

DESCRIPTION

FIG. 1 is a perspective view of a walking treadmill showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, left, top side perspective view thereof; and, FIG. 9 is a perspective view thereof, showing the walking treadmill in a state of use.

The broken lines shown in the figures are for the purpose of illustrating portions of the walking treadmill, which form no part of the claimed design.

1 Claim, 9 Drawing Sheets
